UNITED STATES PATENT OFFICE

170,945

COMBINED MAGNIFIER AND TWEEZERS

Frances Robitschek, Los Angeles, Calif., assignor
of one-half to George Robitschek, Los Angeles,
Calif.

Application April 30, 1953, Serial No. 24,781

Term of patent 14 years

(Cl. D86—10)

To all whom it may concern:

Be it known that I, Frances Robitschek, a citizen of the United States, residing at Los Angeles, California, have invented a new, original, and ornamental Design for a Combined Magnifier and Tweezers, of which the following is a specification, reference being had to the accompanying drawing, forming a part hereof.

Figure 1 is a perspective view of a combined magnifier and tweezers showing my new design;

Figure 2 is a top plan view thereof;

Figure 3 is a side elevational view; and

Figure 4 is an end elevational view looking at the right in Figure 3.

I claim:

The ornamental design for a combined magnifier and tweezers, as shown.

FRANCES ROBITSCHEK.
